UNITED STATES PATENT OFFICE.

JULIUS KAYSER, OF NEW YORK, N. Y.

DESIGN FOR A GLOVE, &c.

SPECIFICATION forming part of Design No. 18,444, dated July 10, 1888.

Application filed March 23, 1888. Serial No. 268,293. Term of patent 3½ years.

To all whom it may concern:

Be it known that I, JULIUS KAYSER, a citizen of the United States, residing at the city of New York, in the county and State of New York, have invented and produced a new and original Design for Gloves, Mitts, Mittens, and the like Articles, of which the following is a specification, reference being had to the accompanying drawing, forming part hereof, which represents a view of the back of a mitt having my design produced thereon.

According to my design I produce dashes or dots *a*, which are separated from each other longitudinally by a space, *b*, and laterally by a space, *c*, at which spaces the goods forming the articles appear, thus producing the effect longitudinally of the glove, one following the other in straight lines, and there are a number of these lines grouped together, as at *d d*

d d d, across which the transverse bars *c'* extend, and there are two or more separated groups of these lines formed on the back of each glove, with a space between them, as 25 shown at *e e e*.

The leading feature of my design consists in the grouped lines of separated dashes or dots, having the transverse bars running across the groups of lines. 30

I claim—

The design for the backs of gloves, mitts, mittens, and the like, substantially as herein shown and described.

Signed at New York, in the county of New 35 York and State of New York, this 15th day of March, A. D. 1888.

JULIUS KAYSER.
